UNITED STATES PATENT OFFICE.

HARRY LEIHR, OF NEW YORK, N. Y.

DESIGN FOR A FINGER-RING.

SPECIFICATION forming part of Design No. 22,192, dated February 7, 1893.

Application filed December 15, 1892. Serial No. 455,308. Term of patent 14 years.

To all whom it may concern:

Be it known that I, HARRY LEHR, a citizen of the United States, and a resident of the city of New York, in the county of New York and State of New York, have invented a new 5 Design for Finger-Rings, of which the following is a specification.

In the accompanying drawing, a perspective view of a finger ring showing my design is 10 shown.

The leading feature of my design consists of a bird with spread wings, in flat relief on the ends of the shanks adjacent to the sides of the gem frame.

15 A is the gem-frame, B the gem, C an initial on the gem, D the shanks, the ends of which are tapered from the sides of the gem-frame.

E is an eagle in flat relief on the tapering end of the shank adjacent to the gem-frame.

F is an arrow held in one of the eagle's 20 talons and G a twig held in the other talon.

Having thus described my invention, I claim as new and desire to secure by Letters Patent:—

The design for a finger-ring, consisting of 25 a gem-frame, shanks tapering from the sides of the frame, an eagle in relief on the tapering part of the shank, an arrow in one talon of the eagle and a twig in the other, substantially as set forth.

30 In testimony that I claim the foregoing as my invention I have signed my name in presence of two subscribing witnesses.

HARRY LEIHR.
